UNITED STATES PATENT OFFICE

2,215,768

HEATER

Chester A. Richardson, San Francisco, Calif.

Original application April 13, 1939, Serial No. 267,698. Divided and this application July 24, 1939, Serial No. 286,229

2 Claims. (Cl. 158—94)

This invention relates to heating devices, and particularly to the heaters used in the ice bunkers of insulated refrigerator cars during winter months to hold the temperature in the car at a safe value. The present application is a division of my application Serial No. 267,698 filed April 13, 1939.

Heretofore uncontrolled charcoal heaters have been the chief reliance and for certain classes of service are satisfactory. There is, however, an active demand for a heater including some automatic temperature controlling means. To secure such control, the most practical fuel is a liquid fuel. Obviously it must be one whose products of combustion are not objectionable, either from the standpoint of danger to service men, or from the standpoint of injury to fruits and vegetables.

For the past several years extensive tests have been conducted in an effort to produce a reliable thermostatically controlled heater. The fuel chosen has been alcohol, because it seems to meet better than any other fuel available, the requirements above outlined.

The importance of close temperature regulation cannot be overstated. Certain classes of fruit should be held within the range of only a few Fahrenheit degrees, otherwise their keeping qualities will be seriously impaired. Slightly greater variations will result in rapid destruction. For example, the permissible range with apples is small, particularly if they have been in cold storage. The temperature for bananas which are not to be ripened in transit must be held within close limits and the temperature is higher than that required for apples. The desired temperature for bananas which are to be ripened in transit is still higher. It follows that a heater suited for general use must be capable of a wide variation of heat output, must be controlled in response to temperature within rather narrow limits, and must include a temperature controlling means which may be set for a wide range of different temperatures and control within close limits at each setting. The adjustment should be easy to make, accurate and capable of accurate indication. This, of itself, produces a very difficult control problem, while the design of a burner which will perform efficiently over a wide range of heat outputs is a problem in itself.

For satisfactory regulation, the best scheme for controlling the heat output is to use an annular asbestos wick burner having a maximum

capacity sufficient to supply the maximum demand, in conjunction with a controller which turns the supply of alcohol to the wick on and off in response to a small temperature change. To permit control of such a burner to the point of extinction it is necessary to use a pilot light, preferably also of the asbestos wick type. The pilot burner furnishes only a negligible amount of heat and will light the main burner wick as soon as fuel is supplied thereto.

In the operation of refrigerator cars, it is necessary to open the hatches over the bunkers for inspection purposes, and on windy days this is likely to result in extinguishing the pilot light. Even in calm weather the slamming of the hatches closed will put out any but a well protected pilot light. The violent slack action often encountered in freight trains also imposes severe requirements. The situation is one in which a very high standard of performance and reliability is required under conditions so variable, and frequently so adverse, that the problem of developing a completely satisfactory heater has proved baffling.

As a result of the use of a float controlled feed to both burners in conjunction with a thermostatic control of the feed to the main burner, a heater was devised by others which operated very successfully under favorable conditions. Basically it was sound, but it could not withstand adverse conditions with sufficient certainty to be commercially adopted as it stood.

The inventions covered by the parent application and this division thereof relate to ancillary features and improvements which have made it possible for this general type of burner to meet the very severe conditions encountered in service.

One feature of novelty forming the subject matter of this divisional application is protection of the pilot light in such a way that it is virtually impossible to blow it out. To accomplish this result, recourse was had to two more or less related arrangements. One is a sheltering chimney, with protecting cap which protects the pilot burner, and at the same time offers an opening which permits the pilot to light the main burner with certainty. The lighting communication with the main burner, however, subjects the pilot flame to the possibility of being blown out, for the reason that a passage large enough for the communication of flame is large enough for the communication of an extinguishing draft.

To meet this situation, the pilot burner flame is sub-divided into two semi-distinct parts, one

of which is adjacent the ignition opening and the other of which is so isolated from the ignition opening that it cannot ignite the main burner but will re-ignite that portion of the pilot burner which is adjacent the ignition opening if this portion should be blown out. The use of a subdivided pilot flame has eliminated almost completely the very troublesome burner failures which were a source of trouble previously.

- 10 Another feature of novelty reserved for the parent application is the use of a series of concentric tubes forming concentric annular ducts in which air flow occurs. These flues protect the encircling alcohol reservoir from undue heating, 15 and apply the heat usefully to a part of the air circulating through the stove.

Another important feature involved directly in the parent application and to an extent in this present divisional application is the use of screens 20 which on the well known principle of the miner's lantern, prevent the passage of flame without preventing the flow of air. These screens are, one within the annular main burner, i. e., between it and the pilot light, except at the ignition opening, and the other outside the main burner. The first of these gives shelter to the pilot light and evens the draft on the inner side of the main burner. The second by serving as a heat conducting and diffusing grid, delivers heat to the 25 rising current of air and resists passage of heat from the burner to the thermostat which last is mounted within the base of the heater.

It would be desirable, if practicable, to mount the thermostat outside the heater so as to respond directly to the temperature of air in the car, but for obvious reasons this is not possible. Accordingly, it is necessary to mount the thermostat in the base of the heater structure where it is affected by air entering the heater and, 30 consequently, operates substantially at car temperature.

The outer screen above-mentioned protects the thermostat from stray heat from the burner and has been demonstrated to contribute very greatly to accurate temperature control of the heater. It also evens the draft and improves the delivery 45 of heat usefully to the circulating air.

An insulating baffle is provided to protect the thermostat from direct heat radiation from the burner, without, however, impairing the circulation of entering air in contact with the thermostat.

The various features above-mentioned are inter-dependent in a considerable degree and produce a successful heater that is substantially protected against accidental failure. Success has been attained by very close coordination of the various features above pointed out.

The invention will now be described with reference to the accompanying drawings which show a commercial embodiment of the invention which has been used in actual service under close observation and has demonstrated that it satisfactorily solves the problem.

65 In the drawings:

Fig. 1 is a side elevation of the complete heater partly broken away in section to show the internal construction.

Fig. 2 is a section on the line 2—2 of Fig. 1.
70 Fig. 3 is a partial plan view of the complete heater.

Fig. 4 is a developed view on line 4—4 of Fig. 2, designed to show the internal construction of the float valve mechanism, the internal construction 75 of the thermostat, and the connections by

which they conjointly control the supply of fuel to the main burner.

Fig. 5 is an enlarged perspective view of the flame divider used on the pilot burner.

Heaters of the type described herein are temporarily placed in the ice bunkers of insulated refrigerator cars at times when no ice is used and the cars are subject to external winter temperatures. To hold them in place and prevent their upsetting and causing fires, they are held in 10 place by chains, following the practice heretofore used with charcoal heaters.

The main supporting framework of the heater comprises a cylindrical base 6 to which is welded an upwardly dished ported bottom 7. Near the 15 upper margin of the base 6 is a circumferential head 8 which serves as a shoulder to assist in positioning the upper cylindrical shell 9 of the heater. This is circumferentially corrugated as shown in the drawings, the purpose of the corrugations being to stiffen the cylindrical shell. A reinforcing band 11 encircles the top of upper shell 9, and a lifting ball 12 is hinged near the top of the shell, so that it may swing down within the upper margin of the shell as clearly indicated in Fig. 3.

The perforated ears indicated by the numeral 10 in Figs. 1, 2 and 3 are provided for the attachment of the chains above-mentioned, but not 30 shown in the drawings.

Mounted concentrically within the shell 9 are two open-ended cylindrical sleeves, an outer sleeve 15 and a slightly longer inner sleeve 16. The inner sleeve is the chimney tube, the outer sleeve has a heat insulating and dissipating function, and preferably comprises a core of sheet asbestos covered on both faces with a layer of thin sheet metal. Such an arrangement is indicated in Fig. 1. The asbestos core may be omitted, in which case sleeve 15 would be simply 40 a metal tube.

The sleeves 15 and 16 are sustained and held centered by radial connectors whose form is best shown in Figs. 1 and 3. Near the bottom of the sleeve 15 there are four stirrup members 13 and 45 near the top of the same sleeve are four radial spacers 14. Opposite ends of these members 13 and 14 are connected to the sleeves 15 and 16 and to the outer shell 9 by means of bolts 17 which pass through tubular spacers 18 as clearly indicated in the drawings.

An annular fuel tank 19 is mounted in the interval between the outer sleeve 15 and the shell 9. It is spaced from the shell 15 to afford a vertical air passage. It rests on the stirrup irons 13 and is removably retained by the radial members 14. It has a filling opening with cap 21 (see Figs. 1 and 3).

Beside rendering the fuel tank removable, this construction protects the fuel tank from overheating and applies usefully heat from the burner to stimulate air circulation. The intervals between the sleeves 15 and 16 and between the sleeve 15 and the inner wall of tank 19 develop a 60 decided chimney effect, promoting the circulation of air through the heater, and this active circulation causes the thermostat to respond 65 more nearly to the actual temperature in the car.

The main burner is mounted in the lower or base section 6 and comprises an annular trough 22 supported by legs 23 and heat insulating spacers 24 on the lower head 7. The annular trough in the burner contains a porous fibrous 75

incombustible wick 25 which in practice is made of asbestos. It is held above the bottom of the trough by a zig-zag spacer 20. Extending from the outer margin of burner 22 at the top thereof 5 is a foraminous baffle or screen 26 which extends outward and downward to the lower margin of the chimney 16, to which it is rigidly attached. The purpose of this screen is two-fold. It regulates the flow of air to the chimney outside the 10 burner and it is kept cool by the up-flowing air, so that it serves effectively as means to resist passage of heat from the burner downward to the thermostat, and to the float chamber hereinafter described.

15 Concentric with and mounted within the burner 25 is a foraminous screen or baffle 27 which extends upward a substantial distance above the burner and which is closed at its upper end by a cap 28. This cap is imperforate except for an opening to receive the pilot light chimney 29 which extends through the cap 28 and which is connected to the baffle 27 as indicated at 31. The cap 28 is held by a bolt 32 which is attached at its lower end to a portion of the framework 25 of the burner 22. A third screen baffle 33 extends horizontally across the space within the baffle 27 and approximately at the upper margins of the pilot burner 34 and main burner 25.

30 The pilot burner 34 is shown as mounted within the annular main burner 25 and tangent thereto. It is of the incombustible wick type and is located adjacent to an ignition opening 35 formed in the foraminous baffle 27 and intended to permit the transfer of flame from the pilot burner to the main burner. Opposite this opening and extending across and dividing the pilot flame is a flame divider or baffle 36 whose form is best shown in Fig. 5. The divider rests on the top of the wick and has a notch 38 for the transmission of flame. The divider is carried by a sleeve which slips onto the upper margin of the pilot burner shell.

40 The upper end of the pilot chimney is closed by a hinged cup-like cap 37 formed as shown 45 with an umbrella-like baffle 37a to offer additional protection against back drafts.

45 The upper end of the main chimney sleeve 16 is closed by perforate hinged cap or baffle 38. This cap 38 offers important protection against 50 the blowing out of the burner. The openings whose form and arrangement are best shown in Fig. 3 are designed to give adequate circulation, and at the same time to afford the maximum possible protection against back-drafts such as 55 occur when the car bunker doors are opened or when these doors are slammed shut.

55 Air for combustion and air to be heated by the stove enter through lateral openings 39 in the base section 6. The combustion air flows 60 through the screen baffles 26 and 33 to the combustion zone and thence upward through the chimney 16. Other air, however, flows upward through the annular passages around the tank 19 and between the chimney 16 and the sleeve 15. 65 This air is heated in greater or less degree and thus serves two useful purposes, i. e., the delivery of heat to the car, and the protection of the fuel tank against over-heating.

70 Mounted within the base portion 6 outside the main burner 25 is the float valve mechanism indicated by the numeral 41 applied to its housing and the thermostat indicated by the numeral 40 applied to its body. The function of the float valve mechanism is to maintain a constant level 75 of fuel supply for both burners. It maintains a

uniform level in housing 41 and from this chamber alcohol is fed at all times through the connections 42 to the pilot burner 34. Thus this burner operates continuously with fuel supplied at constant level.

75 The float chamber 41 also supplies fuel through the connection 43 to the main burner 25. This connection is not constantly open but is opened variably and at times closed by a valve indicated at 44 in Figs. 1 and 3 and subject to control by the thermostat 40.

With this general explanation of the organization of the fuel control, reference will now be made to Fig. 4 in which the fuel control mechanism is shown in greater detail.

15 Fuel is led from tank 19 by pipe 45 to body 41 entering through filter cartridge 46 which is sealed in a chamber 47 by clamp 48. From chamber 47 the fuel rises through tube 49 which contains the seat for needle valve 51, and enters 20 float chamber 52. The needle valve is actuated by float 53, pivoted at 54 and counterweighted at 55. The effect is to maintain fuel in chamber 52 at the level A—A.

25 Connection 42 leads from the bottom of chamber 52 to pilot burner 34.

Connection 43 communicates with chamber 56 in the lower portion of body 41, and fuel flows from chamber 52 to chamber 56 under the control of needle valve 44 which is actuated by lever 30 57 of the thermostat through rod 58. The shell or housing 40 of the thermostat is the expandable element and is made of aluminum. The neutral element comprises two spring bows 59, 61 composed of an alloy sold under the trade 35 name "Invar". This is an iron nickel alloy and has a negligible coefficient of thermal expansion. Thus the bows approach each other in response to falling temperature.

Lever 57 is pivoted to bow 59 and bow 61 reacts 40 against the lever through the adjustable thrust screw 62 which has a graduated milled head 63. An index 64 indicates the adjustment and a spring detent 65 (see Fig. 1) preserves the adjustment. The parts are so arranged that falling temperature tends to open the valve.

Since screw 62 acts on the lever 57 in one way thrust in a valve opening direction, the weight of the parts acts to close the valve and the parts can never be over-stressed. Adjustment of head 50 63 merely changes the temperature at which the valve starts to open. It reaches full capacity with very slight lift, so that the control is sharp, approaching a simple on and off action, rather than graduated opening and closing since such 55 graduation as occurs is within a very small temperature range.

A baffle 50 of heat insulating material protects the thermostat from heat radiating directly from 60 the burner.

No novelty is here claimed for the structure of the float valve per se or for the structure of the thermostat. The thermostat has the desirable characteristic for car service of being little affected by vibration. The double bow arrangement 65 gives a pronounced motion multiplying action, so that small temperature changes produce substantial valve motion at the control point.

While the device has been described in considerable detail and while certain of these details are significant as to precise operation and particularly as to operation under the adverse conditions encountered, the description is illustrative and not limiting, except to the extent expressed in the claims.

What is claimed is:

1. In a heater, the combination of a main burner having a fuel basin and a wick mounted therein; a pilot burner mounted adjacent the main burner; a foraminous screen for protecting the burners and having an ignition opening through which flame from the pilot burner may pass to the main burner; means for turning on and off the supply of fuel to the main burner; and a baffle mounted above the pilot burner arranged to subdivide partially the flame of the pilot burner, whereby the pilot burner is protected against complete extinguishment by draft through said ignition opening.
- 15 2. In a heater, the combination of a main burner having a wick; means for turning on

and off the supply of fuel to said wick; a pilot burner adjacent the main burner and arranged to ignite the same; flame shielding means at least partially separating the flames of said burners but arranged to afford means for the transfer of flame from the pilot burner to the main burner; means for supplying fuel continuously to the pilot burner; and means for subdividing the flame of the pilot burner whereby portions of the pilot burner flame are protected 10 from extinction by drafts while permitting transfer of flame from the pilot burner to the main burner, and between the subdivided portions of the pilot flame.

CHESTER A. RICHARDSON. 15
